United States Patent Office

Des. 210,809
Patented Apr. 16, 1968

210,809

AIRCRAFT

Lloyd C. Stearman, 18545 Sunburst St.,
Los Angeles, Calif. 91324

Filed Feb. 23, 1967, Ser. No. 5,929

Term of patent 14 years

(Cl. D71—1)

FIGURE 1 is a top plan view of the aircraft showing my new design;

FIGURE 2 is a front elevational view of the aircraft; and

FIGURE 3 is a side elevational view thereof.

The dominant features of the design reside in the portions shown in full lines.

I claim:

The ornamental design for an aircraft, substantially as showed and described.
